CONDENSER

Morris H. Bennett, Prospect, Conn., assignor to
 Scovill Manufacturing Company, Waterbury,
 Conn., a corporation of Connecticut

Application August 30, 1934, Serial No. 742,059

4 Claims. (Cl. 175—41.5)

The present invention relates to variable condensers.

An object of the invention is to provide a variable condenser in which the rotor and stator plates are in permanent predetermined spaced relation to each other, and in which this result is secured by a novel method of constructing the condenser, this being accomplished without the use of screws or other adjusting means.

Another object of the invention is to provide a condenser and method of constructing it which will lower the cost of manufacturing.

Another object is to provide a novel rotor plate unit and novel means for insulatably and permanently securing this unit to the rotor shaft.

A further object of the invention is to provide, in connection with the rotor plate unit, a trimmer condenser carried by the frame, one of whose plates is provided with one or more arms making wiping contact with the rotor plate assembly throughout its range of movement.

Still further objects and advantages of the invention will appear from the following description taken in connection with the accompanying drawings, which illustrate a preferred embodiment of the invention, and in which:

Fig. 1 is a top plan view of the preferred embodiment;

Fig. 2 is a side elevation thereof;

Fig. 3 is a transverse section therethrough;

Fig. 4 is an enlarged fragmentary sectional view showing part of the rotor plate unit and its insulated permanent attachment to the rotor shaft;

Fig. 5 is a top plan view, partly in horizontal section, showing the trimmer condenser and its wiping contact arms;

Fig. 6 is a fragmentary vertical transverse sectional view showing in further detail the trimmer condenser structure of Fig. 5, and

Fig. 7 is a fragmentary transverse sectional view through the rotor shaft showing the mounting for it in one of the condenser frame ends.

Referring in detail to the drawings, a condenser frame has front and rear end plates 12 and 14, respectively, and side plates 16 having an integral bottom portion 18 provided with suitable openings 20 for the insertion of the spacing combs hereinafter referred to.

The sides and bottom are provided with slotted re-entrant portions 22, in which are placed a plurality of stator plates 24, the edges of the stator plates protruding through the slots being staked over to lock the stator plates permanently and rigidly in predetermined desired relation.

In accordance with the invention, a rotor plate

unit is provided and includes a plurality of rotor plates 28. In assembling the rotor plate unit, the rotor plates are properly positioned in an assembly jig and a tie bar 30 placed in position with a plurality of tongues 32 on each rotor plate projecting through slots in the tie bar. The tongues are then staked over and the rotor plates of the unit are thereby rigidly and permanently held in desired spaced relation.

The rotor plate tie bar 30 has a channel portion 34 fitting the curved cut-outs in the rotor plates, and, as shown in the drawings, each rotor plate is provided with three tongues staked to the tie bar channel portion and with two tongues staked to the flat part of the tie bar extending along the upper edges of the rotor plates.

This structure, constituting the rotor plate unit, is placed in the frame with the rotor plates properly interleaved with the stator plates, accurate interleaving being insured by the use of spacing combs insertible through openings 20, or by other desired means, and while so held the rotor shaft is placed in position in the frame.

The rotor shaft is provided with a plurality of passages extending diametrically through it and in alignment with each other. These holes are counterbored for the reception of cylindrical porcelain washers 38. A bridge plate or assembly plate 40 has a seating pocket for a second porcelain washer 42. The porcelain washer seats in the shaft and in the assembly plate are deep enough to receive the washers up to about half the height of the washers, and when the assembly plate and washers are in position, a rivet or eyelet is inserted through the washers and through an opening in the washer seat of the assembly plate slightly greater in diameter than the rivet or eyelet. The rivet or eyelet 46 extends through the shaft opening and is then closed over at both ends (Fig. 4), thus providing an exceptionally rigid construction with excellent electrical insulation.

The shaft carrying the assembly plate is placed in the condenser frame and is preferably assembled therein so that it cannot move axially. As indicated in Fig. 4, the assembly plate 40, carried by the shaft, lies within the channel portion 34 of the rotor plate tie bar.

At its forward end the rotor shaft 41 has fixed to it a disc 50 having two stop shoulders 52 and 53 to limit the rotation of the shaft in either direction by contacting a lug 54 punched out of the end plate 12. The disc 50 serves to retain the balls 56 in their raceway 58 in the front end plate and to prevent movement of the rotor shaft axial-

ly to the right as viewed in Fig. 1. A pointed pressure screw 60, carried by the rear end plate 14, supports the other end of the shaft and prevents it from moving to the left.

5 While the rotor plate units are held in interleaved position by combs or otherwise, the assembly plate 40 is soldered along its upper edges, as at 66, to the rotor plate tie bar 30 along both upper edges of its channel 34, whereupon the 10 combs or other holding means may be removed, and the condenser parts are permanently arranged in desired relation.

It will be noted that by this method no adjusting means are necessary for varying the relation 15 of the rotor plates to the stator plates to bring them into the desired adjustment; all the parts are rigidly mounted and there is no adjustable means that can permit the destroying of this adjustment by vibration or otherwise. Moreover, 20 it will be noted that expensive adjusting operations are eliminated.

Referring to the trimmer construction, the frame side 16 is provided with an opening 72, in which is inserted the lower end of a flexible movable trimmer condenser plate 74, whose upper end is movable toward and from a fixed trimmer condenser plate 76 by adjusting nut 78 on a screw 80 carried by the frame side plate. The fixed plate 76 bears on an insulator 82 between itself and the frame side 16 and is provided with an opening through which the screw 80 extends. A sheet of mica 84, or similar material, is located between the fixed and movable plates of the trimmer condenser. The fixed plate 76 is provided 30 with attaching portions 88 passing through openings in the insulator 82 and bent over to lock the fixed plate in position as shown in Fig. 5.

At each end the fixed plate 76 is provided with a flexible arm 90 having a turned-up end 92 bearing 40 on an edge of the channel portion 34 of the rotor tie bar. The fixed plate 76 is also provided with a pair of ears 94 which may be used as soldering lugs to make the connection. It will be noted that the wiper arms 90 conduct energy 45 from the rotor directly to the trimmer plate 76; that a minimum of insulation is employed; and that the movable plate 74, being grounded, acts as a shield to prevent stray electrostatic fields from adjacent trimmers affecting each other. Moreover, it will be seen that there are no joints 50 between the wiper arms 90 and fixed trimmer plate 76 to become defective or to loosen and cause poor connection, leading, in a radio set, to consequent noise. Also, the inductance of the wiper arms is constant regardless of the position of the 55 rotor unit.

What is claimed is:

1. In a condenser, and in combination, a rotor unit comprising a plurality of rotor plates, a tie bar to which the several rotor plates are rigidly secured, a rotor drive shaft, an assembly plate secured in fixed integral metallic relation to said tie bar, an insulating washer between the shaft and said assembly plate, a second insulating washer on the opposite side of the assembly plate, the assembly plate having an opening and the shaft having a diametrical bore in line with said washers, and a rivet passing through said bore, opening and washers and headed over at its ends to secure the shaft and assembly plate together in rigid and insulated connection. 15

2. In a condenser, and in combination, a rotor unit comprising a plurality of rotor plates having arcuate cut-outs about the shaft, a tie bar having a flat portion and a channel portion corresponding to said cut-outs, a plurality of tongues on 20 each of said rotor plates extending into openings in the tie bar and staked over therein, an assembly plate bridging and soldered to the channel portion of the tie bar, and means for rigidly connecting the shaft to said assembly plate. 25

3. In a condenser, and in combination, a rotor unit comprising a plurality of rotor plates having arcuate cut-outs about the shaft, a tie bar having a flat portion and a channel portion corresponding to said cut-outs, a plurality of tongues on 30 each of said rotor plates extending into openings in the tie bar and staked over therein, an assembly plate bridging and soldered to the channel portion of the tie bar, an insulating washer between the shaft and said assembly plate, a second insulating washer on the opposite side of the assembly plate, the assembly plate having an opening and the shaft having a diametrical bore in line with said washers, and a rivet passing through 40 said bore, opening and washers and headed over at its ends to secure the shaft and assembly plate together in rigid and insulated connection. 35

4. The herein described method of assembling the parts of a condenser in permanent adjusted 45 relation which comprises rigidly and permanently securing the stator plates in a frame, rigidly and permanently securing the rotor plates to a tie bar, interleaving the rotor plates with the stator plates, inserting temporary spacing members between the two sets of plates to effect predetermined spacing, mounting the shaft in the frame and confining it against axial movement, and, while the temporary spacing members are still in place, rigidly and permanently securing the shaft 50 to the tie bar. 55

MORRIS H. BENNETT.
